UNITED STATES PATENT OFFICE.

WALTER S. HEINEMANN, OF CHICAGO, ILLINOIS, ASSIGNOR TO THE T. W. HEINEMANN COMPANY, OF SAME PLACE.

CHEST-PROTECTOR.

SPECIFICATION forming part of Letters Patent No. 469,195, dated February 16, 1892.

Application filed December 26, 1891. Serial No. 416,176. (No model.)

To all whom it may concern:

Be it known that I, WALTER S. HEINEMANN, a citizen of the United States, residing at Chicago, in the county of Cook and State 5 of Illinois, have invented a certain new and useful Improvement in Chest-Protecting Garments, which is fully set forth in the following specification, reference being had to the accompanying drawings, in which—

10 Figure 1 represents a perspective view of my garment; Fig. 2, a side elevation of the gore as applied under the arm with the small portion of the garment to which it is attached.

I make a garment composed of chamois- 15 skin, lined, preferably, with woolen material for protecting and keeping the chest warm. The garment is intended to fit closely and snugly to the chest of the wearer.

The object of my invention is to make a 20 portion of the garment elastic, so that it will yield to the movement of the chest caused by respiration or by the bending of the body, but at the same time have the portion which surrounds the armhole of the garment non-elast- 25 ic or non-yielding.

In the accompanying drawings, A represents the body of the chest-protector, the front of which is divided, the two parts being secured together by buttons B or other suitable 30 fastenings.

The body of the chest-protector is made of chamois-skin C C with a woolen lining D, which extends throughout the garment, excepting under the arm.

35 E is a section of knit material, which I manufacture in long strips, which is made so that it is cut in suitable lengths for these garments, each piece being cut having one selvage edge, the other end having an edge 40 that will ravel. In inserting these pieces in my garment I place the selvage edge at the bottom of the garment, and I bind the raw edge or the edge that will ravel with the comparatively non-elastic piece of strong cloth or 45 thin leather F. I insert one of these sections under each armhole of the garment, making two sections E in each garment, which are elastic from the bottom up to the binding F, under the arm-hole of the garment. This 50 binding, being comparatively non-elastic, makes a close fit of the garment entirely around

the arm of the wearer, and does not yield immediately around the arms of the wearer, but will yield because of the character of the knit material of the pieces E from the lower edge 55 of the garment to the binding F.

I find that my chest-protecting garment overcomes the objections to this class of garments heretofore made. Garments of this class, which have no connecting-pieces under 60 the arms connecting the front and back parts, which hang loosely from the shoulders, are apt to fold or curl, and thus cause discomfort rather than protection.

Garments of this class, whose front and back 65 parts are connected under the arms by inelastic material, are open to the objections above named if they loosely fit the body of the wearer and give but little protection to the chest from cold air, and if such garments tightly fit they 70 impede respiration and an easy movement of the body of the wearer.

My garment is made to fit the body of the wearer snugly, and the garment is kept in position by binding the edge of the knit elastic 75 piece that is inserted to connect the front with the back of the garment under the arms at its upper edge with a comparatively non-elastic binding. I preferably knit the inserted elastic strip of the proper width, using what is called 80 a "rib-stitch," for the purpose of giving this strip a suitable amount of lateral elasticity, so that the garment will readily yield in that portion of it where it is desired to admit of easy respiration and a free movement of the 85 body of the wearer without either the front or the back of the garment being displaced or disarranged in any way, making it always certain to protect the body, as desired, under all circumstances.

90 I am aware that elastic sections have been inserted in garments in many and various places and ways, but a knit elastic section made and inserted, as I have described, with a substantially non-elastic binding on its upper edge immediately under the armhole, having a selvage at its lower end and being elastic its entire length, excepting at the binding, makes a garment which I find overcomes 95 all of the objections heretofore found in garments of this class.

Having thus described my invention, what

I claim as new, and desire to secure by Letters Patent, is—

A chest-protecting garment having knit sections connecting the front and back portions of the garment and extending from the armhole to the bottom of the garment, said knit sections having a selvage edge at the bottom of the garment, the upper edge being bound with a comparatively non-elastic bind-

ing immediately under the armhole, making the garment non-yielding around the armhole, but yielding and elastic from the non-elastic binding to the bottom of the garment, as specified.

WALTER S. HEINEMANN.
